ATTORNEY

UNITED STATES PATENT OFFICE

FRANK H. LEE, OF DANBURY, CONNECTICUT

STRAW-HAT CONSTRUCTION

Application filed January 29, 1929. Serial No. 335,816.

This invention relates to hats but more particularly to straw hats.

The principal objects of the invention are to produce a hat of this type which is simple and durable in construction, neat and attractive in appearance and which will provide comfort and ease in wear. Further objects are to provide adequate ventilation, to eliminate stretching and in general to provide a superior hat. Other objects will be in part obvious and in part pointed out hereinafter.

The invention accordingly consists in the features of construction, combinations of elements, and arrangements of parts which will be exemplified in the apparatus herein-after described and the scope of the application of which will be indicated in the following claims.

In the accompanying drawing, in which is shown one of the various possible embodiments of this invention:

Fig. 1 is an elevation of a straw hat,

Fig. 2 is an enlarged sectional view of a portion of the hat shown in Fig. 1,

Fig. 3 is an enlarged sectional view showing the details of construction within the crown, and

Fig. 4 is a detail sectional view.

Similar reference characters refer to similar views throughout the several figures of the drawing.

Referring to the drawing, there is shown a straw hat comprising a crown 5, a brim 6, a band 7, and a sweat band 8. The crown and brim form the body of the hat and are in general constructed in the usual manner by sewing together overlapping rows of relatively coarse straw braid such as the sennit type.

An under brim as 9 of a type of construction similar to the brim proper is secured thereto and this under brim terminates short of the junction of the brim and crown. To the inner marginal portion of this under brim is secured by stitching or otherwise one edge portion of a strip as 10 formed of a series of connected rows of relatively narrow braid. These rows preferably overlap and may be connected by circumferential stitching so that the strip is substantially inextensible. Finer

straw, as for example Milan or similar straw, is preferably used in this strip and it is therefore softer and more flexible than the body of the hat. The strip 10 extends inwardly to the vicinity of the junction of the crown and brim and is visible only upon the under side of the brim.

To the inner edge of the strip 10 is secured a strip 11 of relatively coarser straw similar to that used in the body of the hat. This strip 11 may be in the form of a single wide braid and in the finished hat is preferably disposed between the sweat band 8 and the crown 5, thus acting to maintain these in spaced relation. The advantages of this will be discussed later. The strip 11 may be stitched or otherwise secured to the crown or it may form a loose flap between this and the sweat band. The sweat band 8 is stitched to the hat in the usual manner.

The term "rows" is used in the present application in its broad sense to include separate braids or convolutions of the same braid.

In order to provide adequate ventilation in the hat the crown is perforated as at 12 about its periphery and adjacent its junction with the brim, the perforations passing also through the strip 11. The sweat band is perforated as at 13 and its perforations are preferably in alignment with those in the crown 5 and strip 11. The band 7, instead of being of uniform weave throughout, has a section as 14 of openwork weaving overlying the perforations 12 in the crown. Thus the openings in the sweat band, the strip 11, the crown and the band of the hat are in substantial alignment around the hat and permit the free passage of air therethrough. Ventilation is further assisted by the strip 11 which acts to keep the sweat band spaced from the crown as previously described.

One or more layers or strips 15 of absorbent paper or the like may be interposed between the band 7 and the crown 5 to prevent the staining of the band by perspiration passing through the hat. These strips should be perforated as at 16 in the same manner as the crown and the perforations aligned as already mentioned. One or more narrow strips as 17 of oiled silk or other suitable moisture

proof material may be attached in the customary manner to the lower edge of the sweat band but these should not extend upwardly as far as the perforations in the crown unless they are also perforated in the manner described.

It is customary in this type of hat to apply to the body or portions thereof some form of stiffening substance such as glue or a gelatinous material and various expedients have been employed to provide flexibility in the portions coming in contact with the head of the wearer. In the present construction sufficient flexibility is provided by the use of relatively loose stitching as at 6^a (Fig. 4) in the rows of the brim near its junction with the crown and by applying less stiffening in the vicinity of this junction. The loose stitching permits a limited sliding action of one strip on the next. The perforations may to some extent enhance yielding of the crown. The stitching at 6^a may be of the same type as usual in the remainder of the body of the hat except that the tension on the thread in the sewing machine is reduced, thus providing the looser stitch. The strips 10 and 11 provide a cushioning action which also adds to the comfort of the wearer and they reinforce the body of the hat. By making the strip 10 substantially inextensible, this strip prevents stretching of the hat which is often the cause of considerable trouble to the wearer.

In connection with the advantageous action of this construction, even independently of the ventilating feature, it may be noted that the relatively light or narrow straw 10 passes under the connection or junction, of portions of the brim and crown which are soft as compared with the outer portion of the brim and has attached at its inner end the ring or strip 11 of heavy straw. The latter strip thus gives a needed firmness and prevents a tendency of the brim to tilt out of its plane during the blocking of the hat and also gives an even line for sewing in the sweatband.

It will be seen that there is provided a construction of an essentially practical nature in which the several objects of this invention are attained.

As many other embodiments may be made without departing from the scope of this invention, it is to be understood that all matter herein set forth or shown in the accompanying drawing is to be interpreted as illustrative and not in a limiting sense.

I claim:

1. In straw hat construction, in combination, a hat body including a brim and a crown joined to said brim, a strip of relatively fine straw having one edge portion attached to the under face of the brim at an interval from the junction thereof with the crown and extending inwardly toward the interior of the crown beneath the junction of the brim and crown, and a strip of relatively coarse straw con-

nected to the opposite edge portion of the strip of fine straw.

2. In straw hat construction, in combination, a hat body including a brim and a crown of relatively coarse straw joined to said brim, a strip of relatively fine straw having its outer edge portion attached to the under face of the brim and extending inwardly therefrom beneath the junction of the brim and crown, and a strip of relatively coarse straw connected to the inner edge portion of the first strip and forming an extension thereof within the interior of the crown. 70 75

3. In straw hat construction, in combination, a hat body including a brim, an under brim and a crown of relatively coarse straw joined to said brim, said under brim terminating short of the junction of the brim and the crown, a strip of relatively fine and flexible straw having its outer edge portion connected to said under brim and extending inwardly toward the interior of the crown, and a second strip of relatively coarse straw connected to the inner portion of the first strip and forming an extension thereof within the crown. 80 85 90

4. In straw hat construction, in combination, a hat body of braided straw and including a brim and a crown joined to said brim and a straw strip secured to the under face of the brim and extending to the junction of the brim and crown, said strip being composed of a plurality of overlapping rows of relatively narrow straw braid connected by stitching rendering the strip substantially inextensible. 95 100

5. In straw hat construction, in combination, a hat body including a brim and a crown joined to said brim and having a flexible section adjacent the junction of the brim and crown, and a substantially inextensible strip of straw braid underlying the said junction. 105

6. In straw hat construction, in combination, a hat body including a brim and a crown joined to said brim, and a substantially inextensible strip of straw braid connected to said body and underlying the junction of the brim and crown and extending circumferentially thereof, said strip comprising a plurality of rows of relatively narrow braid connected by circumferential stitching. 110 115

7. In straw hat construction, in combination, a hat body including a brim and a crown of relatively coarse straw braid joined to said brim, a substantially inextensible strip of relatively fine straw braid underlying the junction of the brim and crown and a second strip of relatively coarse straw braid forming an extension of the inner edge of the first strip and extending within the sweat band portion of the crown. 120 125

8. In straw hat construction, in combination, a hat body including a brim and a crown joined to said brim, a substantially inextensible strip underlying the junction of 130

the brim and crown and comprising a series of relatively narrow straw braids connected in overlapping relation by circumferential stitching, and a single relatively wide braid 5 of straw forming an extension of the inner edge of the strip.

9. In straw hat construction, in combination, a hat body of connected straw braids including a brim and a crown joined to said 10 brim, a sweat band within said crown, and a strip of straw braid interposed between the band and the crown at an interval above the junction of the crown and brim and acting to maintain them in spaced relation to provide an air space therebetween, the crown 15 having a series of circumferentially arranged ventilating perforations therein and the strip and band having openings therein communicating with the perforations in the crown.

20 10. In straw hat construction, in combination, a hat body including a brim and a crown formed of straw braids connected by stitching, the braids in the brim adjacent the junction of the brim and crown being relatively 25 loosely stitched together to permit relative movement thereof.

11. In straw hat construction, in combination, a hat body including a brim and a crown formed of rows of straw braid connected by 30 relatively tight stitching, the braids adjacent the junction of the crown and brim being relatively loosely stitched together to permit relative sliding movement of one braid on the next.

35 12. In straw hat construction, in combination, a hat body including a brim and a crown of greater flexibility in the vicinity of the junction thereof than in the remaining portions, the brim and crown being formed of 40 rows of straw braid connected by stitching with the stitching in the brim in the vicinity of its junction with the crown relatively loose to permit relative movement of the rows.

13. In straw hat construction, in combination, a hat body including a brim and a crown, a sweat band within said crown, a strip of relatively fine straw having one edge portion attached to the under face of the 45 brim at an interval from the junction thereof with the crown and extending inwardly beneath said junction, and a strip of relatively coarse straw connected to the opposite edge portion of the strip of fine straw and acting to maintain the sweat band and the crown in 50 spaced relation to provide an air space therebetween.

14. In straw hat construction, in combination, a hat body including a brim and a crown, a sweat band within said crown, a strip of relatively fine straw having its outer edge portion attached to the under face of the brim and extending inwardly therefrom beneath the junction of the brim and crown, and a strip of relatively coarse straw connected to 55 the inner edge portion of the first strip and

being disposed between the sweat band and the crown.

15. In a straw hat construction, in combination, a hat body including a crown having its lower portion soft as compared with its 70 upper portion, a brim including an upper layer having its inner portion soft as compared with its outer portion and an under layer terminating at a point spaced from the crown and having connected thereto a band of straw which is of fine braid as compared to the crown and which extends under the brim to the crown, a strip of coarse straw 75 connected with the inner edge of the strip of fine straw and extending up into the crown 80 and a sweat-band secured in the crown at the inner side of said strip of coarse straw.

In testimony whereof, I have signed my name to this specification this 15th day of January, 1929.

FRANK H. LEE.
